UNITED STATES PATENT OFFICE

149,640

DESIGN FOR A HANDBAG

Max Holzman, New York, N. Y.

Application June 13, 1947, Serial No. 139,669

Term of patent 7 years

(Cl. D87—3)

To all whom it may concern:

Be it known that I, Max Holzman, a citizen of the United States, residing in New York city, county of New York, and States of New York, have invented a new, original, and ornamental Design for a Handbag, of which the following is a specification, reference being had to the accompanying drawing, forming part thereof.

In the drawing:

The cover shown in the drawing is a roll top cover.

I claim:

The ornamental design for a handbag, as shown, and described.

MAX HOLZMAN.
